[57] CLAIM

The ornamental design for a serving plate or similar article, as shown and described.

DESCRIPTION

FIG. 1 is a top plan view of a serving plate or similar article showing my new design;

FIG. 2 is an end elevational view thereof, the opposite end view being the mirror image thereof;

FIG. 3 is a bottom plan view thereof;

FIG. 4 is a sectional view along the length thereof taken along line 4—4 of FIG. 1;

FIG. 5 is a side elevational view thereof, the opposite side elevational view being a mirror image thereof;

FIG. 6 is an enlarged fragmentary top plan view of a portion of the rim of my new design; and

FIG. 7 is a sectional view across the width thereof taken along line 7—7 of FIG. 1.
